176,408

FISHING REEL

Alvah W. Fowler, Fort Worth, Tex.

Application October 26, 1953, Serial No. 27,308

Term of patent 14 years

(Cl. D31—4)

Fig. 1.

Fig. 2.

Fig. 3.

Fig. 4.

Figure 1 is a perspective view of a fishing reel embodying my new design;

Figure 2 is a top plan view thereof;

Figure 3 is a right side elevational view of the reel, and

Figure 4 is a front elevational view thereof.

I claim:

The ornamental design for a fishing reel, substantially as shown.

References Cited in the file of this patent

UNITED STATES PATENTS

D. 135,761 Fanshier ----- June 1, 1943
D. 154,308 Pies ----- June 28, 1949

OTHER REFERENCES

Shakespeare Fishing Tackle Catalog, 1953, page 15,
"The President."

Pflueger Fishing Tackle Catalog No. 61, © 1940, page
13, "The Skilkast."